UNITED STATES PATENT OFFICE.

JOHN FREDRICK KROST AND VERNON J. STEFFEY, OF MANKATO, MINNESOTA.

CLOCK-CONTROLLED LIGHTING CIRCUITS.

Continuation of application Serial No. 342,751, filed December 5, 1919. This application filed July 22, 1920. Serial No. 398,199.

To all whom it may concern:

Be it known that we, JOHN FREDRICK KROST and VERNON J. STEFFEY, citizens of the United States, residing at Mankato, in the county of Blue Earth and State of Minnesota, have invented certain new and useful Improvements in Clock-Controlled Lighting Circuits; and we do hereby declare the following to be a full, clear, and 10 exact description of the invention, such as will enable others skilled in the art to which it appertains to make and use the same.

From a broad point of view, our invention has for its object to provide improved 15 switch mechanism for controlling electric circuits, and to such ends, generally stated, the invention consists of the novel devices and combinations of devices hereinafter described and defined in the claims.

20 The circuit controlled by the switch may, for example, be an electric light circuit of a street or house, or circuit controlling ovens, motors, or the like, but may, as indicated, be any kind of an electric circuit, and especially one that requires to be automatically turned on and off at predetermined times.

25 The improved switch mechanism may be controlled in various different ways, as, for example, by a clock, a thermostat, or a pressure gage, depending on the nature of the use to which the circuit and switch mechanism are applied.

30 Much of the novelty of this invention, however, is directed to the manner in which the switch mechanism is connected to and controlled by clock mechanism and to switch mechanism which is arranged to control commercial light circuits; and in the drawings which illustrate this latter noted application, the arrangement, generally stated, is as follows:

35 The main line switch in the lighting circuit is arranged to be operated and closed at predetermined times, by an electro-magnetic switch operating device comprising two magnets; and for alternately energizing these magnets to effect the automatic action stated, we provide, in suitable shunts or local circuits, a magnet reversing switch 40 operated by or timed to move with the movable member of the main line switch, a clock-actuating magnetic selecting switch connected in opposite sides to the two magnets through the magnet reversing switch, and 45 a secondary clock actuated switch in the

electrical connection of one of the said magnets. The magnetic selecting switch is operated by a clock driven element, preferably in the form of a cam or segmental wheel driven from or with the hour hand of the 60 clock, and the secondary line switch is operated by a clock driven element preferably through certain of the elements that constitute part of the alarm mechanism of the 65 clock.

Obviously, when the alarm mechanism of any standard alarm clock is adjustable in respect to the hands of the clock, the above noted arrangement affords simple means for adjustably setting the time of action 70 of the secondary line switch in respect to the hands of the clock and in respect to the time of action of the so-called magnetic selecting switch. This application is a continuation of the co-pending application of 75 applicants filed December 5th, 1919, S. N. 342,751.

In the accompanying drawings we have illustrated an embodiment of our invention actually put into commercial use and found 80 highly efficient for the purposes had in view. In the said drawings, like characters indicate like parts throughout the several views. Referring to the drawings:

Fig. 1 is a view showing only the face of 85 the clock;

Fig. 2 is a view partly in diagram and partly in section illustrating the relative arrangement of the circuit connections and switches;

Fig. 3 is a fragmentary vertical section showing parts of the clock mechanism;

Fig. 4 is a fragmentary section on the line 4—4 of Fig. 2;

Fig. 5 is an enlarged detail of parts of the 95 alarm mechanism which act upon the secondary line switch;

Fig. 6 is a front elevation of the clock with some parts broken away and showing the inner mechanism and certain of the 100 switches;

Fig. 7 is a plan view of the main line switch and the magnets for operating the same;

Fig. 8 is a view partly in elevation and 105 partly in section on the line 8—8 of Fig. 7; and

Fig. 9 is a fragmentary vertical section on the line 9—9 of Fig. 6.

Of the parts of the clock it is only de- 110

sirable for the purposes of this case to note as follows:

The numeral 10 indicates the case, 11 the dial, 12 the minute hand, 13 the hour hand, 14 and 15 the alarm indicator hand. The numeral 15 indicates a spur pinion carried by the spindle 15^a of the hour hand of the clock and meshing with a gear 16 that is slidably mounted on a spindle 17, and on 10 one face is provided with a cam hub 18 with a single notch, and on its other face is provided with a conical hub 19. The spindle 17, at its front end, carries a gear 20 and a cam pin 21 (see particularly Figs. 3 and 5). Gear 20 meshes with pinion 22 that is connected to the sleeve of the alarm indicating hand 14 and operates the same in a well known manner. In fact, the mechanism so far described, is ordinary alarm 20 clock structure, in which, by rotation of spindle 17, cam pin 21 may be set so that the notch of hub 18 will engage with the same and permit gear 16, under the action of its spring 23, to move toward the left 25 in respect to Fig. 3. This movement of gear 16 toward the left in this arrangement, instead of operating the alarm device, is utilized to operate the so-called secondary line switch, as will hereinafter appear.

30 In this arrangement, to operate the selecting switch, a segmental cam 24 (see particularly Figs. 2, 3 and 6) is applied to the sleeve of the hour hand 12 so that it rotates with the hour hand, and hence, makes one 35 complete rotation every twelve hours. This cam 24 may be given any desired circumferential extent, but as shown, it has about 190 degree extent. As shown, cam 24 operates on the long end of a spring metal U-shaped arm 26, the short arm of which is rigidly secured to an anchoring bracket 27 applied to one of the bearing plates 28 of the clock. Insulated from but secured to the long and relatively movable prong of 40 the spring arm 26 is a contact finger 29 that has two contact points 29^a and 29^b and secured to a fixed prong of the arm 26 but insulated therefrom and from each other, are two relatively fixed contact fingers 30 and 31. 45 The spring arm 26 is a contact finger 29 that has two contact points 29^a and 29^b and secured to a fixed prong of the arm 26 but insulated therefrom and from each other, are two relatively fixed contact fingers 30 and 31. 50 The elements just described constitute what is herein designated as the primary magnet selecting switch.

The switch herein designated as the line selecting switch comprises a fixed contact 55 32 and a movable contact 33. Fixed contact 32 is insulated from, but secured to bearing plate 28. Movable contact 33 is insulated from but secured to the free end of a lever 34 (best shown in Figs. 2, 5 and 6, but also shown in Figs. 3 and 9). Lever 34 is pivoted to bearing plate 28 at 34^a, its vibratory movement is limited by a slot and screw connection 35, and said lever is yieldingly drawn upward by a coiled spring 36 anchored to said plate 28. Normally, how-

ever, cam pin 21 on spindle 17, acting on the main surface of hub 18, will hold cone hub 19 toward the right, in respect to Figs. 3 and 5, and this cam hub will cam switch lever 34 downward and hold contact 33 away from contact 32, as shown in Fig. 2.

The leads of the main line circuit are indicated by the characters *a* and *b* and a local light or service circuit, such as a house, factory or store circuit, is indicated at 37 (see Figs. 2 and 7).

The main switch, among other things, as here illustrated, comprises two laterally spaced relatively fixed spring contacts 39 and two co-operating movable contacts 40^a and 40^b. Contacts 39 are supported from an insulating base *c*, and each is electrically connected to one of the leads of the local circuit 37. The main line leads *a* and *b* are connected, respectively, to the movable contacts 40^a and 40^b. Said two contacts 40^a and 40^b are both carried by an insulating head 40, which in turn, is carried by a plunger 41 that is preferably of copper or other non-magnetic metal, and at its outer end is provided with a magnetic solenoid core 42 that works freely in a sleeve 42^a supported by brackets 42^b on base *c*. Fixed on the sleeve 42^a are two electro-magnetic coils 43 and 44 arranged, axially, one ahead of the other.

A switch which is herein designated as the secondary magnetic selecting switch, comprises two fixed contacts 45 and 46 and a movable contact blade 47, which latter is carried by the plunger.

The numeral 50 indicates a wire that connects the contact finger 29 of primary magnet selecting switch to the main line lead *a*, through a metallic bracket 48 on the insulating base *c*. The numeral 51 indicates a wire that connects the contact 30 of the primary magnet selecting switch to the movable contact 33 of the line selecting switch. The numeral 52 indicates a wire that connects the fixed contact 32 of the line selecting switch to one terminal of the coil 43. The other terminal of the coil 43 is connected by a wire 53 to the contact 46 of the secondary magnet selecting switch. The numeral 54 indicates a wire that connects the contact 31 of the primary magnet selecting switch with one terminal of the coil 44, and the numeral 55 indicates a wire that connects the other terminal of said coil 44 to contact 45 of said secondary magnet selecting switch. The numeral 56 indicates a wire that connects the blade 47 of the secondary magnet selecting switch to one of the contacts 39 of the main line switch. (See Fig. 8.)

To provide for throwing the clock control of the switches entirely out of action, we have provided a spring retracted plunger 57 (see Fig. 9) mounted in the bearing plates 28 and 28^a of the clock. This plunger

normally stands in its inoperative position shown in Fig. 9, but when pressed toward the left, it will engage the lever 34 and hold the same in its inoperative position shown in Fig. 2; and to hold said plunger in its said operative position, a clip 58 is pivoted to the plate 28^a of the clock and adapted to be moved over the inwardly pressed outer end of said plunger.

10

Operation.

The operation of the device described is substantially, as follows:

In the arrangement illustrated, cam 24 is set so that it will come into engagement with the long plunger of spring arm 26 at about 8 o'clock and will run out of engagement therewith at about 10:00 o'clock, and during such interval, said cam, acting on said arm, will hold contact point 29^a of finger 29 engaged with contact finger 30, thereby closing the circuit to magnet coil 43 at that point, but it will be noted that this circuit is still broken between contacts 32 and 33 of the line selecting switch. At this time, circuit through magnet coils 44 is broken by separation of contact point 29^b from contact 31, so that the plunger 41 of main line switch will then be as shown in Fig. 2 and main line circuit will be open between contacts 39. If we assume that alarm indicating hand 14 is set at 7 o'clock, as shown in Fig. 1, then at 7 o'clock, the single notch of hub 18 of gear 16 will come into line with relatively fixed but adjustable cam pin 21, and spring 23 will then force gear 16 toward the left, carrying with it cone hub 19, and this will permit spring 36, acting on arm 34, to move contact 33 into engagement with contact 32, thereby completing the circuit through the magnet coil 43. When magnet coil 43 is energized, it will, acting on core 41, move plunger 41 between main line contacts 39, and thereby close the main line circuit through local circuit 37, and turn on the lights or perform any other operation accomplished by closing of the main line circuit.

A few minutes of movement of the hour hand, and hence, of the gear 18 will cause the notch of hub 18 to cam gear 16 again to the right, thereby causing cone hub 19 to again force contact 33 away from contact 32, thus breaking the circuit through magnet coil 43, but leaving the plunger 41 engaged with contacts 39 and hence, the main line circuit closed.

However, the breaking of the circuits through coil 43 does not wait for the above noted separation of the contacts 33 from 32 because contact blade 47, by the final part of the movement of the plunger 41 into engagement with contacts 39, will move said blade out of engagement with contact 46, thereby instantly breaking the circuit

through magnet coil 43. This same movement of the plunger 41 brings blade 47 into engagement with contact 45 of secondary magnet selecting switch, thereby closing the circuit through the coil 44 at that point, but the circuit through said coil 44 is still broken between contacts 31 and 29^b, so that said magnet 44 does not yet operate to retract the plunger 41. However, at about 10 o'clock, cam 24 will run out of engagement with long prong of spring arm 26 and said prong will then spring back to normal position, thereby carrying contact 29^b into engagement with contact 31, thus completing the circuit through magnet 44, and the latter being energized, will quickly remove plunger 41 back to its normal position shown in Fig. 2. This return of plunger 41 to normal position quickly breaks the circuit through magnet coil 44 between contacts 45 and 47 and said contact 47, by re-engaging contact 46 again closes the circuit at that point through coil 43, but the circuit through said magnet coil 43 will still be open between contacts 32 and 33 of the line selecting switch.

If pinion 15 and gear 16 are to be made of the same diameter, then the above noted opening and closing periods and resulting opening and closing of the main line switch will take place during each twelve hours, but it is desirable for most purposes that the opening and closing of the main switch take place only during p. m. hours, that is, during the evening and before midnight, and to provide for this, we simply make the gear 16 of twice the diameter of pinion 15 so that the pinion 16 and its notched hub 18 will be given a complete rotation only once for each twenty-four hours and then when the notch of hub 18 will come into engagement with cam pin 21 between noon and midnight, thereby operating the secondary line switch only during that interval. Obviously, during the twelve hours between midnight and noon, cam 24 will operate the line selecting switch while the plunger 41 is in position shown in Fig. 2, but this will not energize magnet 43 because the circuit will then be broken between contact 32 and 33 of line selecting switch and will not energize magnet 44 because its circuit is then broken between contacts 45 and 47.

It has already been noted that the timing of line selecting switch may be varied in respect to the timing of the magnet selecting switch. By the simple expedient of shifting the hands of the clock in respect to their driving gears, the timing of cam 24 may also be varied in point of time of operation. It can, of course, be understood that the hands of the clock, after being shifted, would be set for the proper time indication.

It will be noted that in the above described arrangement, the main line is closed

through the local circuit 37 by co-operating contacts located on each side of the line and that when the main switch is open, the local circuit will be broken on both sides. The 5 clock-controlled means for operating the switch mechanism involves very considerable novelty, but, as already indicated, from a broad point of view, the novel switch mechanism herein disclosed may be controlled by any automatic means or even by 10 hand controlled switch operated at will. This switch mechanism will be found highly desirable for use very generally for turning electric circuits on and off, either automatically or by manual control from a distant 15 point.

What we claim is:

1. An electrical device having in combination one source of current, a main line circuit 20 connected to said source, a local circuit, a main line switch for energizing said local circuit from said source, a pair of electromagnets for moving said main switch in opposite directions, said main line circuit 25 having branches, each controlling one of said magnets, time controlled elements in said branches of said main line circuit to control the same to alternately and periodically operate said magnets, and means for opening 30 said branch circuits by movement of said main line switch.

2. The combination with a main line circuit and a main line switch, of an electromagnet actuator for said main line switch, a 35 branch circuit including leads connected across the main line and including the electromagnetic actuator, and a magnet reversing switch operated by the movable element of said main line switch having electrical 40 connections for setting said actuator for reverse actions in alternate order, said connections of said magnet reversing switch being included in said branch circuit.

3. The combination with a main line circuit 45 and a local circuit, of a main line switch for connecting said local circuit in said main line, a magnetic actuator comprising a pair of magnets for said main line switch, said main line circuit having a branch including 50 a circuit maker and breaker and a magnet reversing switch operated by the movable element of said main line switch and having electrical connections for alternately cutting the magnet of said actuator out of action 55 after the movable element of said main line switch has been given operative movement in one direction or the other.

4. The combination with a main line circuit 60 and an automatic controller of a main line switch for opening and closing said main line circuit, a two-magnet actuator for said main line switch, primary and secondary selecting switches operative by said automatic controller, one after the other, and connected 65 across the main line the said secondary

switch being interposed in the electrical connection between one side of said primary selecting switch and said actuator magnets.

5. The combination with a main line circuit and an automatic controller, of a main line switch for opening and closing said main line circuit, an electro-magnetic actuator for said main line switch, primary and secondary selecting switches operated by 75 said automatic controller and connected with said actuator in series in a shunt circuit across the main line, and a magnet reversing switch operated by the movable element of said main line switch and having electrical connections for reversing the action of the magnets of said switch actuator.

6. The combination with a main line circuit and an automatic controller, of a main line switch for opening and closing said main line circuit, a two-magnet actuator for 80 said main line switch, primary and secondary selecting switches operative by said automatic controller, one after the other, and in series with said actuator in a shunt circuit connected across the main line the said secondary switch being interposed in the electrical connection between one side of said primary selecting switch and said actuator magnets, and a magnet reversing switch 85 operated by the movable element of said main line switch and having electrical connections for reversing the action of the magnets of said switch actuator.

7. The combination with a main line circuit and an automatic controller, of a main line switch for opening and closing said main line circuit, an electro-magnetic actuator for said main line switch, a controller 100 actuated primary selecting switch, a controller actuated secondary selecting switch, 105 said switches and electromagnetic actuating devices being connected in a circuit across the main line and said secondary switch being interposed in the electrical connection between one side of said primary selecting 110 switch and said electromagnetic switch actuating device, and adjustable means for varying the times of action of said primary and secondary selecting switches.

8. The combination with a line circuit and 115 a clock, of a main switch for opening and closing said line circuit, an electromagnet actuator for said main switch, a clock controlled circuit across the main line including the electromagnet actuator, and a magnet 120 reversing switch actuated by movement of said main switch.

9. The combination with a line circuit and 125 a clock, of a main switch for opening and closing said line circuit, a two-magnet actuator for said main switch, a magnet circuit breaker and reversing switch, a clock controlled shunt circuit across the line having one part including one magnet of the two magnet actuator and one pole of the magnet 130

- reversing switch and another part including the other magnet of the two-magnet actuator and the other pole of the magnet reversing switch.
- 5 10. The structure set forth in claim 9, the first part of said circuit having a primary clock-controlled switch, and a secondary clock controlled switch therein.
- 10 11. The structure set forth in claim 9, said circuit including a clock controlled switch having two sets of contacts, one set adapted to close one part of said circuit and the other set adapted to close the other part of said circuit.
- 15 12. The combination with a line circuit and a main switch for opening and closing said line circuit, a solenoid for closing the switch, a solenoid for opening the switch, a circuit including a time-controlled primary switch, a time controlled secondary switch and a circuit breaker and solenoid reversing switch, said primary switch and said secondary switch being adapted to close the circuit through one solenoid.
- 20 13. The structure set forth in claim 12, said primary switch having two sets of contacts, one set co-operating with said secondary switch to close said circuit through one solenoid and the other cooperating with the circuit breaking and solenoid reversing switch to close the circuit through the other solenoid.
- 25 14. The combination with a line circuit and a clock, of a main switch for opening and closing said line circuit, an electro-magnetic actuator for said main switch, a clock-actuated selecting switch, a clock-actuated secondary line switch, said switches and electro-magnetic actuating devices being connected in series across the main line and said secondary switch being interposed in the electrical connection between one side of said selecting switch and the said electro-magnetic switch actuating device, the mechanism of said clock including an adjustable cam pin, a laterally movable spring pressed gear equipped on one side with a hub having a single notch for engagement with said cam pin, and said gear, on its other side having a cone that directly operates said secondary line switch.
- 30 15. The combination with a line circuit and a clock, of a main switch for opening and closing said line circuit, an electro-magnetic actuator for said main switch, a clock-actuated selecting switch, a clock-actuated secondary line switch, said switches and electro-magnetic actuating devices being connected in series across the main line and said secondary switch being interposed in the electrical connection between one side of said selecting switch and the said electro-magnetic switch actuating device, and means adjustable to vary the time of action of said secondary switch.
- 35 16. The combination with a line circuit and a clock, of a main line switch including fixed space contacts and co-operating movable plunger, an armature connected to said plunger, electro-magnets having reverse actions on said armature, a magnet reversing switch including fixed spaced contacts and a co-operating contact blade moved by said plunger alternately into engagement therewith, a magnet selecting switch including insulated spaced fixed contacts and a movable contact arm having contact points alternately engageable with said latter fixed contacts, a clock actuated cam operative on the movable arm of said selecting switch, a secondary line switch including a fixed and a movable contact, clock actuated means for opening and closing said secondary line switch, a wire connecting one side of said line circuit to the two contact points of the movable arm of said selecting switch, a wire connecting one of the movable contacts of said selecting switch to one of said switch actuating magnets, a wire connecting the other side of said latter noted magnet to one of the fixed contacts of said reversing switch, a wire connecting the other fixed contact of said selecting switch to one of the contacts of said secondary switch, a wire connecting the other contact of said secondary switch to the other of said electro-magnets, a wire connecting the other side of this latter noted magnet to the other fixed contact of said reversing switch, and an electrical connection between the movable blade of said magnet reversing switch and one side of said line circuit.
- 40 17. The combination with a line circuit and a clock, of a main line switch for said line circuit, including a movable contact, reversely-acting electro-magnets operative to move the movable member of said main switch to and from circuit closing position, a magnet reversing switch operated by the movable member of said main switch and including fixed contacts connected, one to each of said magnets, and a movable contact connected to one side of the main line, a clock actuated secondary line switch, and a clock-actuated magnet selecting switch, said latter switch including insulated fixed contacts connected, one to one of said magnets and the other to one of the contacts of said secondary switch, the other contact of said secondary switch being connected to the other electro-magnet, said selecting switch including also a movable contact alternately engageable with said fixed contacts, and itself connected to one side of the main line.
- 45 18. The combination with a light circuit and a clock, of a main line switch for said light circuit, including a movable contact, reversely acting electro-magnets operative to move the movable member of said main switch to and from circuit closing position,

a magnet reversing switch operated by the movable member of said main switch and including fixed contacts connected, one to each of said magnets, and a movable contact connected to one side of the main line, a clock actuated secondary line switch, and a clock-actuated magnet selecting switch, said latter switch including insulated fixed contacts connected, one to one of said magnets and the other to one of the contacts of said secondary switch, the other contact of said secondary switch being connected to the other electro-magnet, said selecting switch including also a movable contact

alternately engageable with said fixed contacts, and itself connected to one side of the main line, and means for varying the time of action of said secondary switch in respect to the time of action of said selecting switch.
